Patent expires January 4, 1963

4 Claims. (Cl. 68—176)

1

The present invention relates to an improved apparatus for the continuous production and liquid treatment of threads (within which term, as used in this specification and claims, are included filaments), more particularly of artificial threads.

In the manufacture of artificial threads it is known to pass the thread issuing from the spinneret over a pair of mutually inclined rotating rollers acting together as a thread-storing, thread-advancing device, in which at least one roller is positively driven, and to subject the thread while on the rollers to treatment with liquids such as dilute acid, aqueous formaldehyde and the like for the purpose of assisting coagulation or of hardening the threads. After such treatment it is usual to apply a washing treatment, e. g., with water. In order that the acid or other treating liquid may be confined to its own portion of the rollers and not reduce the efficiency of the washing treatment in the next portion of the rollers, it has been proposed to separate the successive treating portions or zones of the rollers by complete (i. e. continuous) peripheral flanges. In such an arrangement it is necessary, when starting up, whether initially or after a break in the thread, to lift the thread by hand over the obstructing flange.

Furthermore, during spinning there develops at times a tendency for the spacing between loops of thread on the rollers to widen very slightly beginning at the end of the rollers nearest the spinneret. This widening is usually very small between any two adjacent loops, but the total cumulative effect of such widening over the considerable number of loops to the first flange may be to increase the total distance along the rollers occupied by these loops by an amount equal to the space between one or two loops. Therefore, unless the loops are lifted over the obstruction by hand, a wrapper will form adjacent the flange, causing a break. Accordingly, in order to be practically utilizable at all, such flanges must be so located as to be readily accessible to the operator, a condition often not feasible to meet in modern apparatus of the type here involved. Moreover, the use of such flanges entails extra attention and labor in any event.

Likewise, there is sometimes a tendency for the spacing between loops to narrow, also starting from the end nearest the spinneret. This, however, does not give serious trouble because bunching does not occur even if the loops are not moved back across the flange.

It is an object of the present invention to provide a device whereby the thread is enabled to

2

cross the flanges separating the successive treating portions of each roller without having to be lifted over by hand. Other objects will be apparent from the following description.

These objects are achieved by the present invention which consists in the provision of flanges which, instead of extending continuously around the respective rollers, are provided with suitable gaps through which the loops of thread will pass during spinning or when the thread traverse is being started or re-established.

According to the invention the rollers carrying the thread to be treated are provided with one or more flanges, each of which is interrupted by a gap. If desired, the lower roller may be furnished with a gapped flange situated at the end of the acid treatment zone, and the upper roller with a gapped flange some distance farther along.

I prefer to dispose the flanges on each roller in pairs about an inch apart, with their gaps at opposite sides of the roller.

The gaps are preferably of a width not less than one-sixth of the length of the flange (i. e. of the circumference of the roller), thus subtending an angle of not less than 60° at the axis of the roller at that point.

The gapped flange may be turned out of the solid during the manufacture of the roller, or may be separately made and attached to the roller, or may be in the form of a split ring of springy material sprung on to the roller.

The invention is illustrated more or less diagrammatically by the accompanying drawings in which

Figs. 1 to 4 are fragmentary views in side elevation of rollers or godets provided with gapped flanges in various desirable forms and arrangements within the invention, in which wherever the path of the thread is indicated, the showing is for an upper roller;

Figs. 5 and 6 are fragmentary views of a pair of rollers illustrating how the thread "cross-over" from one side of a flange to the other is permitted by the flange gap; and

Fig. 7 shows a portion of another pair of rollers embodying the invention.

In the arrangement illustrated in Figure 1, two gapped flanges 1, 2, are provided in spaced relationship on a guide roller 3, the gaps, 4, 5, in these flanges being disposed not immediately opposite each other but in staggered positions for good separation of the treating zones on the roller.

In the arrangement shown in Figure 2, a single flange, 6, is provided with a gap, 7.

In the arrangement shown in Figure 3, two flanges, 10, 11 are provided in which the gaps, 8, 9, are on diametrically opposite sides of the roller thereby attaining still better separation than the embodiment shown in Fig. 1.

Figure 4 shows a roller provided with an interrupted helical flange.

Fig. 7 shows diagrammatically a portion of a pair of thread-storing, thread-advancing rollers 12, 13, in operation. Flange 14, on the lower roller, and flange 15, on the upper roller, are shown lying between successive loops of thread at a time when the loops are not moving longitudinally along the rollers due to widening of the spaces during spinning or due to a start up.

The flanges may be convex or prismatic in cross-section, and are preferably chamfered on both sides or at least on one side so that the thread may pass smoothly through the gap.

In a preferred embodiment of the invention I use two gapped flanges or two pairs of gapped flanges, so situated on the rollers that the first marks the end of that zone in which acid liquid is applied to the thread, and the other lies about two-thirds of the distance along the wash-water zone. The flanges have their ends bevelled, and the radial angle between the centres of the gaps on the two flanges is about 180°, each gap subtending at the axis of the roller an angle of at least 60°.

Example

Filaments of viscose artificial silk issuing from a spinneret immersed in a coagulating bath are led in the well-known manner to a pair of rotating skew rollers, each 45 inches long and 6 inches in diameter, set about 24 inches apart, the lower roller being inclined with a dip of 1 in 80 downwards towards the entrance end, the upper roller being horizontal. The thread sets itself round the pair of rollers in loops spaced about five-sixteenths of an inch apart. A spray of dilute acid is applied to the first 20 inches of the lower roller and is prevented from extending along the roller by a pair of flanges one inch apart, each one-sixteenth of an inch thick, projecting one-eighth of an inch above the surface of the roller, situated 24 inches from the initial end of the roller, and each provided with a four-inch gap between bevelled ends, the gaps being in staggered relationship. To the part of the roller beyond this flange wash-water is supplied. A third similar single flange, situated 14 inches from the second of the pair of flanges but on the upper roller and with its gap on the side of the roller opposite to the gap in the first flange, serves to separate the first washing from the later washings less contaminated with acid.

On starting up or more particularly during spinning at times when the spacing between the loops tends to widen or narrow, the thread, on reaching each flange, remains on the near side of the flange until the rotation of the roller carries the gap into a suitable position, when the thread at once crosses through the gap to the further side of the flange. After passing the flanges in this manner where necessary, the loops of thread set themselves in helices about five-sixteenths of an inch apart throughout the length of the pair of rollers, and each gapped flange is observed to lie between two successive loops of the thread.

The foregoing will be further apparent upon reference to Figs. 5 and 6 in which only the portion of the rollers adjacent a flange F on the top roller is shown. The thread T travels from the

spinneret (not shown) on the right toward the left as seen in these views and lies in helical loops along the length of the rollers. Furthermore, the loops to the right of flange F are, in this particular case, tending to move longitudinally toward the left, and loop L on the top roller is shown being held by the flange in an abnormal position. It is readily apparent that if loop L remained permanently to the right of the flange, successive loops would bunch together forming a wrinkle and causing a break. However, this difficulty is overcome by the present invention because of the gap provided in the flange, which gap permits the loops to pass from one side of the flange to the other. Fig. 6 shows how the thread will slip through the gap in the flange when the roller has rotated enough to bring the gap into proper position. After a further 180° rotation of the roller, loop L will pass through the flange and can move into its normal position to the left of the flange.

In the foregoing example the gapped flanges are circular and placed at right angles to the axis of the roller to which they are fitted. The invention is not limited, however, to circular flanges so disposed. If desired the flanges may be helical so as to fit on to the roller obliquely; in such cases they should preferably not exceed in pitch the natural spacing of the loops of thread as the thread advances along the pair of rollers.

Numerous methods of wrapping the thread on the rollers may be used in connection with the present invention. For example, one way this has been done is to wind an auxiliary thread by hand in loops around the pair of rollers while these are stationary, in approximately the path to be followed by the freshly spun thread. The trailing end of the auxiliary thread is then attached to the new thread, and at the same time the rotation of the rollers is begun. The new thread is thus drawn over the rollers by the auxiliary thread. In apparatus having continuous peripheral flanges, the loops were prevented, once the approximate traverse had been established, from adjusting themselves longitudinally along the rollers by the flanges as previously explained; but by means of applicant's invention, the loops cross the interrupted flanges, where necessary, through the gaps as described above.

It will be apparent that although my invention finds its main application in the manufacture and treatment of artificial threads, it is also of use when for any reason it is desired to treat any kind of thread with two or more different liquids in successive zones of the traverse of the thread along a pair of mutually inclined rollers.

I claim:

1. Apparatus for the continuous production and treatment of thread comprising a pair of mutually inclined, rotating rollers acting together as a thread-storing, thread-advancing device along which the thread traverses in a succession of helical loops at spaced intervals, wherein at least one of the rollers is provided with at least one peripheral flange separating adjacent treatment zones, each flange being interrupted for a distance of not less than one-sixth of its length by a gap to provide a cross-over for the thread.

2. Apparatus as claimed in claim 1, in which at least one roller is provided with two peripheral flanges each interrupted by such a gap, the gaps being in staggered relation to one another.

3. Apparatus as claimed in claim 1, in which each such flange has chamfered edges and ends.

4. Apparatus as claimed in claim 1, in which

at least one such flange is in the form of an interrupted helix on the roller and of a pitch not exceeding the pitch of the helical loops of thread.

SYDNEY WARREN BARKER.
